UNITED STATES PATENT OFFICE

2,595,990

WHIRLING TOY

Albert M. Steiner, Cincinnati, Ohio

Application April 11, 1950, Serial No. 155,187

2 Claims. (Cl. 46—49)

1

This invention relates to children's toys and is particularly concerned with a whirling or spinning toy which combines features of color display and sound making.

The general type of toy to which the invention relates and the means provided for imparting the whirling motion are old and well known. The invention is concerned with particular improvements in the construction and mode of operation which greatly increase the toy's attraction for children and even for adults.

It has long been conventional to whirl a single disc having a variegated color pattern imposed thereon by means of a looped cord inserted through a pair of apertures in the central part of the disc. The disc is first wound on the cord manually by swinging it continuously around the cord with a circular motion and with one end of the looped cord held in each hand. After the cord has been wound, the ends are pulled outwardly from both sides of the disc and a fast rotary whirling motion is imparted to the disc by the unwinding of the string. After the string has become unwound, the continued rotation of the disc resulting from its inertia winds the string in the reverse direction and a reasonably adept manipulator can thereby keep the disc rotating for an indefinite period of time. The same general arrangement has also been employed on discs having saw teeth on the outer periphery. These can be manipulated by a child in such a way as to saw paper, cardboard or even soft wood. Other embodiments of this general idea have also been provided.

One of the objects of the present invention has been to improve the general type of structure just described to provide a toy which is of rigid and reinforced construction and which can be used for an indefinite period of time.

Another object has been to provide a toy in which a sound effect is produced by the normal operation of the toy and one in which the sound note is not constant but varies from time to time with the whirling motion.

Another object has been to provide a toy in which a particularly pleasing color pattern is obtained on the sides of the toy during the whirling operation and one in which the color pattern constantly changes with the rotation of the toy.

Other and further objects and advantages will be apparent from the further and more detailed description of the invention when considered in conjunction with the drawings illustrating a preferred embodiment and a modification thereof, and in which:

2

Figure 1 is a side elevation of a toy constituting a preferred embodiment of the invention assembled and in position for use.

Figure 2 is an end elevation of the structure shown in Figure 1.

Figure 3 is an exploded view of the side of the toy which is visible in Figure 1.

Figure 4 is an exploded view of the reverse side of the toy.

10 Figure 5 is an enlarged side elevational view of the side of the toy shown in Figure 1 which is partially broken away to illustrate the assembly of the elements illustrated in Figure 3.

Figure 6 is a cross sectional view along the line 6—6, Figure 1.

Figure 7 is a cross sectional view along the line 7—7, Figure 2.

Figure 8 is a view similar to Figure 5 illustrating a modified form of the invention.

20 Figure 9 is a sectional view along the line 9—9, Figure 8.

As best illustrated in Figure 1, the entire toy comprises three main elements: the main disc designated generally as 10, the continuous cord 25 length 11 which is passed through a pair of bores in the main disc, and the handle elements 12 and 13 in which the cord ends are secured.

The main disc 10 is formed of a pair of circular plates 14 of identical configuration, the plates being spaced apart and connected by flat transverse baffles 15 or spacer elements which extend radially inward at spaced points around the circumference of the disc. In the preferred form of assembly, the plates and baffles are formed from a hard surfaced plastic material and alternate baffles are formed integrally with opposite plates. As illustrated in Figures 2 and 7 particularly, the extended edge of each baffle is inserted into a groove 16 in a rib 17 on the inner surface of the opposite disc and secured there by adhesive. This results in a particularly strong and effective structure and facilitates the fabrication of the elements.

On the outer edge surface of each plate, a peripheral flange 18 is formed. A similar flange 19 is positioned inwardly of the peripheral flange, and the two flanges, 18 and 19, define a circular recess or groove 20 in which the color discs and screens described below are adapted to be loosely positioned. A plug 21 extends outwardly from the surface in the central area of the plate and has a pair of bores 22 formed through it into which the cord ends are adapted to be threaded. A second recess 23 is formed between the outer edges of

45 the plug 21 and the inner flange 19. Apertures 50 55

24, preferably of rectangular configuration, are formed in this recess and sound reeds 25 are secured over these apertures preferably on the inner side of the plates as illustrated in Figures 2 and 7. The reeds may also be molded into the plates when they are formed. A rotatable sound screen disc 44 comprising a round flat disc having a portion cut away to form a slot or aperture 45 is adapted to be loosely positioned in the recess 23 when the various elements of the device are assembled.

The component elements which produce the color and sound effects are illustrated in Figures 3 and 4. The color disc which has been designated generally as 26 is a thin flat disc formed from cardboard, plastic or the like and having a central aperture which is adapted to engage with the outer surfaces of the flange 19. The exact color arrangement or pattern on this disc is not essential to the invention, but in the preferred form shown, the disc is divided into a plurality of sections 27 which are positioned radially around the periphery, and these sections divided into stripes 28 of contrasting colors or color arrangements. Preferably, the pattern is composed of the three primary colors, red, blue and yellow, so that upon rotating the toy, the colors mix and produce varying color patterns. This disc is adapted to be placed directly in the recess 20 and to be covered by the color screen plate 29, the exact configurations of which are not material except that it has a central aperture of the same size as that of the color disc 26 and is likewise adapted to fit on the inner flange 19. After the color disc 26 and color screen plate 29 have been assembled in this order, the end cap 30 having a central aperture 31 is fitted on the plug 21. This end cap may also have a pair of oval apertures 32 formed therein to facilitate the outward passage of sound as illustrated in Figure 1. On its inner surface, the end cap 30 has an outer flange 41 which is adapted to engage with and be adhesively secured to the flange 19, thereby maintaining the end cap in fixed position while the color disc 26 and the color screen plate 29 being loosely mounted are free to rotate relative to the disc. In this embodiment the inner flange 39 fits into a peripheral recess 40 in the plug 21, but is not secured thereto. (See Figure 6.)

There exists between the screens, the color disc and the main disc, a certain amount of friction, and thus once the toy is spinning, the screens and color discs rotate with the main disc, or in other words are stationary relative to the main disc. However, each time the toy is reversed, the inertia of the freely mounted screens and color discs causes them to overtravel at the reversal and change their positions relative to the main disc. Thus, each time reversal occurs, the color pattern of the disc is changed. It is also at this time, that is, upon reversal, that the sound screen discs 44 shift position relative to the reeds. It can be seen, therefore, that the differences in weights of the screens and discs, and the differences in the friction between these elements and the main disc or between the elements themselves, both contribute to a differential of overtravel between the various freely mounted elements. Obviously, the color patterns thus provided not only change with each reversal but vary in practically an infinite number of combinations.

The views shown in Figure 4 illustrate the various elements which may be positioned in the

5 recess 20 on the opposite side of the disc from that illustrated in Figure 1, but again the exact configuration and number of discs does not form an essential element of the invention. Those 10 illustrated include a color disc 33 having somewhat larger segments 34 and somewhat wider stripes 35 from that previously described. Also included are a color screen plate 36 having a pair of oval shaped apertures 37 formed therein and a second color screen plate 38 adapted to be fitted on top of the first. The construction of the end cap 30 is the same as that previously described, and the assembly of the elements is the same except for the inclusion of the additional color screen plate.

In the modification of the invention illustrated in Figures 8 and 9, the color screen plate, here designated 42, is somewhat similar in contour to that previously designated 29, except 20 that it includes an aperture 43 to permit the passage of sound from the reed 25. In this construction, the color screen plate 42 is formed integrally with a sound screen disc previously 25 described as 44. The inner flange 19 is omitted from the construction of the plate 14 and the flange 41 is omitted from the construction of the end cap 30, the end cap being adhesively secured 30 to the plug 21 along the inner flange 39 of the end cap 30. With this construction, the disc 42, which is adapted to function both as a sound screen and color screen, is free to rotate without interference from the flanges 19 and 41.

In the operation of the device, the elements 35 are assembled in the manner described and the disc is whirled in exactly the same way as in the prior art structures. The centrifugal force 40 created through the whirling of the disc forces out the air which was originally contained between the pair of circular plates 14, creating a 45 partial vacuum in this area. The existence of the vacuum causes new air to be sucked through the apertures 24 in the sides of the discs and through the sound reeds 25 which creates a whistling or singing noise which varies with the speed of the rotation of the disc and the relative 50 positioning of the sound screen plate 44 with respect to the apertures 24. It will be noted that the construction of the plate 44 is such that it never entirely closes both of the apertures 24 but always closes a portion of at least one. The color effect is caused by the rotation of the particular color disc, such as 26 or 33 and varies with the positioning of the various color screen plates such as 29, 36 or 38.

55 Obviously, the exact sound and color effects may be varied within rather wide limits. Different types and numbers of reeds may be employed and sound screen plates of different configuration may be used in conjunction with them. The color effects permit an even wider variation and if desired and with slight modifications in structure the end cap may be made detachable so that the color discs and color screen plates may be replaced when desired with others of a different pattern.

Having described my invention, I claim:

1. A rotatable toy comprising a pair of spaced plates, spacer elements interconnecting said plates, a sound making element mounted in the side wall of one of said plates, a color panel mounted on the exterior surface of the same plate as the sound making element, and means 70 for intermittently screening the sound element during rotation of the toy and simultaneously screening portions of said color panel.

2. A rotatable toy including a pair of spaced plates and spacer elements interconnecting said plates, a sound making element mounted in the side wall of one of said plates, a color panel likewise mounted on the same side wall and a screen element mounted for free rotation with respect to the toy, said screen element being adapted to screen intermittently portions of the color panel and the sound making element.
